1

This invention relates to hollow electrical resonators and to electron discharge devices embodying such resonators.

In electrical apparatus it is well known to employ hollow resonators for a variety of purposes. One important use of hollow resonators is in electron discharge devices in which an electron beam is passed through the resonator, the resonator, the resonator serving to impart velocity modulation to the beam or serving to extract energy from a velocity modulated beam. The physical dimensions of the resonator determine the resonant frequency thereof and it will be appreciated, therefore, that in general, the higher the resonant frequency the smaller the dimensions of the resonator. It has been suggested to operate a resonator at a harmonic frequency of higher order than the fundamental or first harmonic frequency to which the resonator is tuned so as to allow the dimensions of the resonator to be increased compared with the dimensions of a resonator having a fundamental frequency equal to that of the desired harmonic frequency. However, even if a resonator is operated in such manner the dimensions of the resonator may still be inconveniently small and this is particularly so when the resonators are employed in electron discharge devices where it is frequently necessary to provide for some adjustment of tuning. Tuning is frequently effected by the insertion of one or more tuning plungers and in such cases the space available in the resonator for the insertion of the plunger or plungers may be so small that the range of tuning adjustment possible is very limited and, furthermore, if it is desired to apply to or extract energy from the resonator by means of a coupling loop inserted in the resonator, there is a tendency for flashover to occur between the resonator and the coupling loop, particularly when operating at high powers, if the clearance between the wall of the resonator and the coupling loop is small.

The present invention is concerned with the problem of increasing the size of a resonator without the change in size altering substantially the frequency of the resonator and without substantially changing its mode of oscillation. It will be understood that various modes of oscillation can be set up in hollow resonators and for any particular purpose for which the resonator is to be used it is desirable that the mode of oscillation remains unchanged whatever the ultimate size of the resonator may be.

When resonators are constructed to operate at harmonic frequencies of higher order than the

2

fundamental frequency, at least one voltage node or point of zero electric field is set up intermediate the extremities of the resonator and I have found in considering the problem with which the present invention is concerned that whilst the dimensions of the resonator in planes at right angles to the electric field set up in the resonator when the latter is excited, largely determine its resonant frequency, it is, however, possible to increase the 5 depth of a portion of the resonator, the depth of the resonator being measured along the lines of the electric field which extend directly between opposite walls of the resonator, without substantially changing the resonant frequency or the 10 mode of oscillation of the resonator providing that the change in depth occurs in the vicinity where, in operation, a voltage node is set up.

According therefore to one feature of the present invention there is provided a hollow electrical 15 resonator which is such that when excited a voltage node can be set up intermediate the extremities of the resonator and wherein the resonator comprises portions between which there is an abrupt change in depth, the change in depth occurring in the vicinity of said voltage node.

By virtue of the present invention it is, therefore, possible to provide a resonator in which one portion thereof is increased in depth compared with another portion without the change 20 in depth substantially altering the resonant frequency of the resonator or its mode of oscillation. The invention can be applied to a wide variety of resonators and in particular to resonators of the form employed in electron discharge devices of the velocity modulation type. In these resonators, 25 particularly those used in klystrons, portions of the sides of the resonator are disposed close together to form a gap through which an electron beam is caused to pass, the gap providing a lumped capacity. In such a resonator the depth of the resonator in the vicinity of the lumped capacity does, to some extent, determine the resonant frequency of the resonator and hence for any particular frequency the dimensions of that 30 portion of the resonator are fixed. The depth, however, of that portion of the resonator beyond the lumped capacity can be increased providing the change in depth occurs in the vicinity of a voltage node. This portion of increased depth 35 can therefore readily accommodate a tuning plunger or plungers and/or a coupling loop without the disadvantages referred to above.

According, therefore, to another feature of the invention there is provided a hollow electrical 40 resonator of which portions of the opposite sides

of the resonator are disposed in proximity to one another to afford a lumped capacity and the resonator is such that when excited a voltage node can be set up at a position remote from the lumped capacity and wherein the depth of that portion of the resonator beyond said position is abruptly increased, the change in depth occurring in the vicinity of said voltage node.

According to another feature of the invention, an electron discharge device is provided employing a hollow resonator which is such that when excited a voltage node can be set up intermediate the extremities thereof and in which opposite sides of the resonator are formed to provide a gap through which the electron beam of the device can be caused to pass in the direction of the depth of the resonator and wherein that portion of the resonator remote from the gap is abruptly increased in depth, the increase in depth occurring in the vicinity where said voltage node is set up.

In order that the said invention may be clearly understood and readily carried into effect it will now be more fully described with reference to the accompanying drawings in which:

Figure 1 is a sectional view through a resonator illustrating one mode of operation thereof,

Figure 2 is a longitudinal section of an electron discharge device embodying a resonator according to the invention,

Figures 3 and 4 are cross-sectional views of electron discharge devices employing different forms of resonators according to the invention, and

Figure 5 is a cross-sectional view through a different form of resonator according to the invention.

Referring first to Figure 1 of the drawing, the reference numeral 1 indicates in cross-section a hollow rectangular resonator. Such a resonator can be excited in a fundamental mode so as to set up electric field components within the resonator extending in the same direction. Furthermore, if the resonator is excited at a harmonic frequency of higher order than the fundamental frequency determined by the dimensions of the resonator, at least one voltage node will be set up intermediate the extremities of the resonator, a single voltage node being set up when the resonator is operated at the second harmonic, i. e., at twice the fundamental frequency and occurring, for example, in the plane indicated by the dotted lines 2-2 in Figure 1. I have found that whilst the dimensions of the resonator shown in Figure 1 in planes at right angles to the electric field largely determine the resonant frequency of the resonator, it is possible to increase the depth of the resonator without changing its resonant frequency or its mode of oscillation providing the change in depth occurs in the vicinity where the voltage node is set up. The depth of the resonator is the dimension measured along the lines of the electric field which extend directly between opposite walls of the resonator. Thus, according to the invention it is possible to increase abruptly the depth of the resonator shown in Figure 1 in the manner indicated by the dotted lines without substantially changing the resonant frequency of the resonator and without substantially changing its mode of oscillation providing the increase in depth occurs in the vicinity of the voltage node, i. e., in the plane 2-2. The enlarged portion of the resonator can be considered as a resonator oscillating

at its fundamental frequency since as there is a voltage node in the region where the change in depth occurs, obviously the nodal surface can be replaced by a metal conductor without disturbing the field of distribution appropriate to the mode of oscillation under consideration, i. e., the mode in which the electric field components are as indicated by the arrows in Figure 1. Theoretically, in this mode of oscillation the frequency of the resonator is dependent only on its dimension in planes transverse to the electric field components as stated above and not on the depth of the resonator although it is possible that if the depth of the resonator exceeds one-half of the wavelength in air of the oscillations set up, other modes of oscillation may occur with nodal planes perpendicular to the arrows shown in Figure 1. In practice, however, such modes have not been detected.

Figure 2 of the drawings illustrates a resonator constructed according to the invention as applied to an electron discharge device of the velocity modulation type. In this figure the reference numeral 3 indicates generally a hollow resonator which is of toroidal form and the opposite sides of which are provided with a pair of centrally disposed apertures 4 and 5 forming a gap through which an electron beam can be caused to pass. The electron beam emanates from a cathode 6 surrounded by a focussing shield 7. Electrons, in passing through the gap in the resonator, become velocity modulated and such velocity modulated stream may be utilized in any of the manners known in the art. In the example shown in the figure the electron beam is directed towards a reflecting electrode 8 maintained at a suitable potential to cause the electron beam to be reflected back through the gap in known manner so that the device shown can function to generate self-maintained oscillations. The electron beam in passing through the resonator causes the latter to be excited, setting up electric field components which extend across the gap substantially parallel to the axis of the resonator shown in Figure 2. The depth of the resonator shown in Figure 2 is, therefore, its dimension parallel to the axis thereof. With the form of resonator shown in Figure 2 it is possible by suitable phasing of the electron beam to cause the resonator to operate at a harmonic of higher order than its fundamental frequency, with the result that a voltage node or nodes can be set up intermediate the center of the gap and the periphery of the resonator. It is obvious, however, that only the odd-numbered higher harmonics, namely the third, fifth, seventh, etc., in which a voltage loop or point of maximum electric field occurs at the central gap formed by apertures 4 and 5, can be used with a centrally-located electron beam. In accordance with the invention, in order to increase the size of the resonator the latter comprises in effect two portions 9 and 10, the portion 10 of the resonator being abruptly increased in depth compared with the portion 9, the change in depth occurring in the vicinity where a voltage node is set up. In the resonator shown in Figure 2 the provision of the gap gives rise to a lumped capacity and the effect of this lumped capacity results in the dimensions of the portion 9 of the resonator being fixed both in its radial dimensions and in its depth for any particular frequency. Thus the portion 9 of the resonator cannot be increased in depth without changing the resonant frequency. However, according to the invention it is possible

to provide the portion 10 of increased depth without substantially changing the resonant frequency or the mode of oscillation of the resonator, thus affording a portion of increased dimensions which can more easily accommodate tuning plungers or coupling loops.

In the resonator shown in Figure 2, it is arranged that the central portion 9 of the resonator lies within an evacuated envelope 11, whilst the portion 10 of the resonator lies outside the evacuated envelope. In order to reduce losses to a minimum due to the presence of the envelope the wall of the latter where it lies between the sides of the resonator is disposed at a position corresponding to a position where, in operation, a voltage node is set up. In the example shown, the envelope 11 is disposed at a position substantially coinciding with the position where the increase of depth of the resonator occurs. It will, however, be appreciated that although in the example shown the wall of the envelope coincides substantially with such position, it is possible, providing that the resonator is operated at a suitable harmonic frequency at which more than one voltage node is set up, for the wall of the envelope and the point at which the change in depth occurs to be situated at different nodes. The construction of resonator shown in Figure 2 is employed where the resonator is to be operated at the fifth harmonic. In the fifth harmonic two voltage nodes are set up intermediate the central apertures 4 and 5 and the outer periphery of the resonator portion 10. In Figure 2 the change in depth is located at the second voltage node from the apertures 4 and 5, and the envelope 11 is located as close to the second node as possible. However, it may be preferred to increase the depth of the resonator at a position corresponding to the first voltage node from the apertures 4 and 5 and to dispose the envelope at the second voltage node.

Whilst the invention has been described above as applied to two constructions of resonators, it will be understood that the invention is not limited thereto, since it can be applied to other types of resonators. For example, Figure 3 of the drawings illustrates the invention as applied to an electron discharge device having an envelope 11' and containing a resonator 3' having an annular gap 12 through which a beam of electrons is arranged to flow radially. The resonator shown in Figure 3 is of toroidal form generated by revolving the resonator section shown in Figure 2 about an axis at right angles to a line passing through the gap and having portions 3' and 9'. A central annular cathode 13 is employed and the reflecting electrode comprises a ring 14 surrounding the annular gap.

Figure 4 shows the invention as applied to a resonator for use with an annular beam of electrons. In this case the resonator is also of toroidal form and is generated by revolving the resonator section shown in Figure 2 about an axis parallel to a line passing through the gap and having portions 9'' and 10''. The gap 15 in this resonator is also of annular form, whilst the cathode 16 is ring-shaped for generating an annular beam of electrons and the reflecting electrode 17 is also of ring shape. The electrodes are all mounted within envelope 11'.

Figure 5 of the drawings illustrates a further form of resonator having portions 9''' and 10''' to which the invention can be applied. This resonator is of toroidal form but instead of the sides of the inner resonator portion 9''' being parallel

they are divergent from the gap at the center of said inner portion to the periphery thereof. A resonator of this form has a depth which gradually increases from the center to the periphery of the inner portion and in accordance with the invention at the point where a voltage node is set up an abrupt change of depth occurs. The word "abrupt" referred to herein is used in order to distinguish from a gradual change in depth which occurs with the inner resonator portion of the form shown in Figure 5. The invention can also be applied to resonators for use with ribbon-shaped beams of electrons. The cross-section of a resonator for use with such a beam may be the same as that shown in Figure 2, the apertures in the resonator, however, being of elongated form and the general shape of the resonator conforming to the shape of the apertures. The invention is, of course, not limited in its application to the particular forms of discharge devices shown in Figures 2, 3 and 4.

While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

1. A cavity resonator having a predetermined fundamental frequency, including an enclosed hollow body formed with apertures in the opposite walls and a gap adjacent said apertures, the distance between the inner walls of said body adjacent said apertures being substantially less than the distance between said walls at portions remote from said apertures, the distance between the walls being increased abruptly at a point intermediate said apertures and the most remote portions of the resonator in the vicinity of a voltage node when excited at an odd harmonic of higher order than said fundamental frequency.
2. A cavity resonator having a predetermined fundamental frequency including a hollow conducting body having a central aperture therethrough, said body comprising first and second portions of substantially different depths joined together, the depth of said body being abruptly increased at the junction of said portions, the change in depth being located at a point intermediate said central aperture and the outer periphery of said body in the vicinity of a voltage node when said resonator is excited at the fifth harmonic of said fundamental frequency.
3. A cavity resonator having a predetermined fundamental frequency including a hollow conducting body comprising first and second portions of substantially different depths joined together, the depth of said body being abruptly increased at the junction of said portions, the change in depth being located in the vicinity of a voltage node when said resonator is excited at a harmonic of higher order than said fundamental frequency, the opposite walls of said portion of lesser depth having curved parts spaced from each other to define a gap.
4. A cavity resonator having a predetermined fundamental frequency comprising a hollow conducting body formed by a surface of revolution and having apertures in oppositely disposed sides

thereof, the transverse section of said resonator outwardly from said apertures comprising a first portion of an annulus having spaced curved reentrant parts defining said apertures and a second portion of an annulus remote from said apertures and of greater depth than and joined at an extremity of said first portion of an annulus, there being an abrupt increase in the depth of said resonator body at the junction of said portions, the change in depth being located in the vicinity of a voltage node when said resonator is excited at a harmonic of higher order than said fundamental frequency.

5. A cavity resonator as claimed in claim 4 in combination with an electron discharge device having a cathode for supplying a beam of electrons, and an electrode in the path of said electrons, said cavity resonator being positioned between and having its apertures aligned with said cathode and said electrode, whereby said resonator may be excited at a frequency considerably higher than a resonator of uniform depth equal to the depth of said second resonator portion.

6. An electron discharge device having a cathode for supplying a beam of electrons, an electrode lying in the path of said electrons, and a cavity resonator having a predetermined fundamental frequency positioned between said cathode and said electrode and including a hollow conducting body, said hollow conducting body having curved reentrant portions centrally thereof, the inner ends of said reentrant portions being spaced from each other to form a gap and being provided with apertures adjacent said gap and through which the beam path lies, the spacing between the walls of said resonator at said reentrant portions being substantially less than the spacing between the walls remote from said portions, the change in dimensions increasing abruptly at a point intermediate said gap and the most remote part of the resonator body in the vicinity of a voltage node when the resonator is excited at an odd harmonic of higher order than said fundamental frequency.

7. An electron discharge device having an annular cathode for supplying electrons in an annular beam and an annular electrode in the path of said electrons, a cavity resonator adapted to be excited at a harmonic of its fundamental fre-

quency and positioned between said cathode and said electrode and including a hollow toroidal resonator, the apertured portion of the resonator next adjacent the electron path being formed with aligned apertures through which said path extends and a gap adjacent said apertures, the distance between the opposite walls of said resonator adjacent said gap being substantially less than the distance between the walls of said resonator at those portions remote from said gap, the distance between the walls changing abruptly at a point intermediate the gap and the portion of the resonator farthest removed from said gap, said change in dimension occurring in the vicinity of a voltage node when said resonator is excited at an odd harmonic of higher order than said fundamental frequency.

8. A resonator having a predetermined fundamental frequency comprising a hollow conducting body formed by a surface of revolution and having apertures in oppositely disposed sides thereof, the transverse section of said resonator outwardly from said apertures comprising two diverging lines adjacent said apertures and a portion of an annulus remote from said apertures and joined at an extremity of said lines, there being an abrupt increase in the dimensions of said cross section in the direction extending from said apertures to the portion of said resonator remote from said apertures at the juncture of said lines and said portion of said annulus, said abrupt increase being located in the vicinity of a voltage node when said resonator is excited at an odd harmonic of higher order than said fundamental frequency.
